UNITED STATES PATENT OFFICE.

JACK MEDLOCK, OF GRANDFIELD, OKLAHOMA.

BAG HOLDER.

Application filed April 18, 1927, Serial No. 184,690. Renewed November 13, 1928.

This invention relates to devices for holding and dispensing paper bags used so generally in retail stores and has for its object the construction of a bag holder providing greater facilities for the insertion, retention and dispensing of bags and arranged to be supported from or by any of the means, devices or equipment commonly provided or encountered in stores generally.

One object of the invention is to provide a device of this character providing a construction lending itself readily to manufacture by machine operation.

One feature of the invention resides in a yoke approximating in form an inverted U having the lower opposite ends of the yoke bent inwardly to form spaced walls providing opposed inset flat bag-embracing jaws having alined openings to receive a bag supporting nail or rod and having means to retain the nail or rod when inserted.

A further object of the invention is to provide a bag holder of this type having its upper portion slotted in alinement to provide a plurality of supporting means operating independently and in conjunction.

The advantages will be more fully appreciated by reference to the following detailed specification when read in connection with the accompanying drawing forming part thereof, and in which:

Figure 1 is a perspective view of my bag holder in bag supporting position,

Figure 2 is a side elevation thereof showing the relation of the bag-embracing jaws and supporting nail to the bags.

Referring to the drawings by numerals, 1 indicates the rear or wall side of a bag embracing yoke, the front side of which is indicated at 2. This yoke, as will be seen from Figure 1 is formed of flat metal, bent by stamping, or otherwise, to form a yoke approximating in shape an inverted U, the metal of the legs at opposite sides at the bottom or open end of the U being bent inwardly at 3, thence upwardly as at 4 and finally rearwardly, as at 5, to form spaced walls at opposed sides of the yoke, these walls providing flat bag-embracing jaws inset from the yoke.

The side of the yoke which in one position of use of the holder, would rest against a wall from which the yoke is supported, and which I have indicated by the numeral 1, is provided adjacent to its upper end with a key-hole slot 6 therein effective to seat over and retain the headed end of a nail, stud, etc., pro-

jecting from the wall and thereby to support the holder from the wall. At a point horizontally in alinement, the opposite side of the yoke which as shown, curves inwardly upward to join with the wall side 1, is provided with an elongated slot 7 therein, the metal within the area of the slot being bent upwardly as at 8 and its end downwardly as at 9 to form an auxiliary supporting hook 65 adapted for engagement with various projecting surfaces to support the bag holder therefrom where a wall stud or nail is not available.

The slots 6 and 7 cooperate and are used 70 conjointly in suspending the bag holder say, as one of a series, on a horizontally extending wire or rod, (not shown) such as is frequently used for bag suspending purposes. In this arrangement the bags and bag holders will 75 hang inclined, since slots 7 will be above slot 6. The angle at which the bags incline present their edges at an angle facilitating the separation of one from the mass by the fingers.

The bag-embracing jaws of my holder are 80 perforated as at 10, Fig. 2 to permit the insertion therethrough of a nail, pin or rod 11, a nail being illustrated. The holders are all 85 designed to be made of one standard size and preferably the standard size of a holder and nail, are made to coincide. The perforations 10 in the spaced walls of the bag-embracing jaws act as guides for the nail 11, permitting 90 a nail to be driven through a packet of bags inserted between the jaws of the holder, the spaced walls in which these perforations are 95 formed acting as guides for the nail while it is being driven through the bags and as guards thereafter. It is not intended that the bag supporting nails should be driven 100 through the rear wall 1 into the store counter or wall. On the contrary in order to facilitate refilling the nails or rods used are of a length to extend to the back wall with the nail and the bags threaded thereon supported by the walls of the bag-embracing jaws. To prevent the nail or rod from sliding out of the holder a pivoted retaining closure 12 is provided for the front nail opening 10. 105 When a holder is empty or nearly so, in order to refill it, it is only necessary to move the closure to one side and pull out the suspending nail, threading or driving the same through a new supply of bags as previously 110 indicated.

Having described my invention what I

claim and desire to secure by Letters Patent is:

I claim:

1. A bag holder formed of a strip of flat metal bent to form a yoke approximately of the shape of an inverted **U**, the lower ends of the strip being bent inwardly, upwardly and thence outwardly forming spaced walls providing flat inset bag embracing jaws at opposite sides of the yoke, and having aligned openings therethrough to the rear wall of the rearmost jaw, providing guiding and supporting means for a suspending nail or rod for bags embraced between said jaws, and a movable closure for the front nail opening to retain the nail in bag suspending position, said yoke being formed with means for engagement by a supporting medium.

2. A bag holder formed of a strip of flat metal bent to form an integral yoke approximating in shape an inverted **U**, the opposite lower open ends of which form bag embracing jaws, and are bent in rectangular shape and perforated to house and retain the opposite ends of a bag-suspending rod or nail, and said yoke adjacent to its upper end being provided with aligned slots arranged for use conjointly, one of said aligned slots being formed to engage the head of an embedded fastener to support the holder independently of the other slot.

3. A bag holder formed of a strip of flat metal bent to form a yoke approximating in

shape an inverted **U**, the ends of the strip at the lower open end of the **U** being bent inwardly to provide opposed inset bag embracing jaws, provided with means to receive and retain a bag supporting nail or wire, the sides of said yoke, adjacent to its upper end being slotted to provide aligned slots, one of which is adapted by configuration to receive and retain a nail or other supporting head and the metal from the area of the other slot being bent upwardly and backwardly to form an auxiliary supporting hook, said aligned slots additionally permitting said yoke to be strung and suspended on a horizontal supporting wire or rod extending through said aligned slots.

4. A bag holder comprising a yoke approximating an inverted **U** in shape with one of its lower ends bent back upon itself to form a box perforated in one face only, to receive and guard the end of a bag suspending nail or wire inserted through an aligned perforation in the other lower end of the yoke, with means detachably to hold in said other lower end the wire or nail so inserted.

5. A bag holder having bag embracing jaws terminating in rectangular box-like ends with aligned nail-guiding perforations therein, the innermost box-like end having its outer face, only, perforated to provide through its inner face, a guard for the end of a bag suspending nail or wire.

JACK MEDLOCK.
